United States Patent Office.

GEORGE WAIDE REYNOLDS, OF SMETHICK, ENGLAND.

Letters Patent No. 70,018, dated October 22, 1867.

IMPROVEMENT IN SKIRT-WIRE.

The Schedule referred to in these Letters Patent and making part of the same.

TO ALL WHOM IT MAY CONCERN:

Be it known that I, GEORGE WAIDE REYNOLDS, of Smethick, in the county of Stafford, of England, have invented an "Improved Manufacture of Bands or Strips for Crinolines;" and I do hereby declare that the following is a full and exact description thereof, reference being had to the accompanying drawings.

In preparing strips of steel for conversion into crinolines, it has been usual to cover them with cotton plaiting, the cotton threads being laid around the strips sufficiently close to hide the steel. It has also been proposed as a cheaper operation to cover the steel with paper. This latter plan, however, has this disadvantage, viz., that crinolines made from such paper-covered steel bands will, when worn, produce a rustling sound. Those bands also present some disadvantage in the coupling of their ends, and when the steel breaks the broken ends are at once free and dangerous, which is not the case with steel strips having a plaited covering.

In order, however, to secure to some extent the economical advantage of the paper-covered strips or bands, I propose to employ a compound covering, which will combine, to some extent, the advantage of both plans, and have the same slight appearance, without being so costly as the close cotton plaiting. To this end I first cover the strips of crinoline steel with white or other suitably toned paper, in any well-known or approved manner. Over the steel strips, so covered with paper, I apply an open-plaited covering, using for that purpose the ordinary plaiting or braiding machinery, availing myself of the color of the paper for producing the effect of a thick cotton covering, while the paper serves effectually to prevent the edges of the strips from cutting the cotton plaiting. In the accompanying drawing I have shown, on an enlarged scale—

Figure 1, a strip of steel coated with paper, the edges being lapped, to insure a complete covering of the metal; and at

Figure 2 I have shown the paper-covered strip, with the open-plaited covering applied thereto.

By this combined means of covering metal strips I am enabled, with a small expenditure of cotton, to obtain as good a result as if the steel bands were thickly plaited with cotton, and also to produce the plaiting with great expedition.

I claim skirt-wire, first covered with an envelope of paper or similar material, applied as described, and then an open-braided covering or jacket, substantially as set forth.

Done at London this 27th day of August, 1867.

GEORGE WAIDE REYNOLDS.
